MICROPHONE CONTROL

Carl Dreher, Los Angeles, Calif., assignor to
Radio-Keith-Orpheum Corporation, a corpora-
tion of Maryland

Application March 24, 1931. Serial No. 524,854

5 Claims. (Cl. 179—146)

The present invention relates to a method of and apparatus for moving and rotating the microphones and equipment associated therewith, such as baffles and absorbers, used in the electrical pick-up of sounds, for any purpose, but more particularly for use in connection with sound recording, as in the production of talking motion pictures, in such a manner as not to interfere with the photography of the production being 10 filmed.

In the production of talking motion pictures, the present practice is to locate the microphones used in picking up the voice and auxiliary sounds, produced upon the set, upon a boom which is utilized to move the microphone to the most favorable pick-up location at any instant. The boom and microphones are kept out of the range of the cameras. Certain other microphones are located in the flies or are hidden behind parts of the scenery or stage property. At present it is the practice to arrange the microphones prior to the commencing of a "shot" and in the event that the sound picked up is not sufficient for recording purposes, the picture must be stopped and the microphone relocated. Further in the present arrangement, it is necessary that an intermediary direct the location of the boom instead of the operator at the mixer, which latter must, however, direct the operations of the former.

20 The object of the present invention is to overcome each of the above noted difficulties.

It is a further object of this invention to provide a new mounting for a microphone pick-up system.

35 It is a still further object of this invention to provide means whereby the mixer operator may directly control the motion and location of the recording apparatus in order to obtain the best recording results.

40 It is a further object of this invention to provide a system and apparatus which will permit the shift of the microphones to obtain the best results without interrupting the performance of a "shot" being filmed.

45 These and other objects of my invention will become apparent from the following specification taken in connection with the appended drawing.

In accomplishing the objects of my invention, I provide for each microphone, whether it is mounted upon a boom or upon an ordinary stand, a rotating arrangement by which the orientation of the microphone may be controlled. This arrangement is preferably of the interlocking type in which a controller, rotated by the mixer operator, operates the motor controlling the point-

ing of the microphone, which latter will follow the control motor, as it is rotated under the direction of the operator. The movement of the two motors may be made proportional, or an auxiliary indicating device may be provided as desired to indicate the orientation of the microphone being controlled.

A similar arrangement may be provided for moving the booms from which the microphones are hung, and also for moving the microphones through a vertical angle as required.

The interlocking control system thus provided may be utilized to direct the moving and orientation of the microphones on the sound movie stage without in any way interfering with the photography, for the purpose of securing the optimum acoustic conditions and the best possible pick-up.

Having thus briefly described my invention, attention is invited to the accompanying figures in which:

Fig. 1 shows a boom mounted microphone with its operating motor;

Fig. 2 shows the control motor for controlling the operating motor of Fig. 1;

Fig. 3 shows the control motor indicating dial and control knob;

Fig. 4 is a wiring diagram showing one arrangement for connecting the interlocking operating motor and control motor; and,

Fig. 5 shows an optional circuit arrangement for connecting the interlocking operating and control motors.

Referring now more particularly to Fig. 1, 11 shows the microphone boom or beam from which is suspended in accordance with my invention, an operating motor 12 by means of the hanger 13. The motor hanger 13 is secured by any appropriate means to the stator of the operating motor. From the motor shaft 14 is suspended a microphone hanger 15 which serves in turn to suspend the microphone amplifier 16 to which is attached, the usual microphone 17. The microphone amplifier is connected by means of the cable 19 passing through the boom 11, in the usual manner, to the mixing panel. The cables 21 and 23 are provided to appropriately connect the stator and rotor respectively of the motor 12 to the stator and rotor of the control motor 25 (Fig. 2) as will be described more fully hereinafter.

Referring now more particularly to Figs. 2 and 3, the control motor 25 is mounted in a convenient location near the mixing panel so as to be under the control of the mixer operator. The shaft 24 of the motor 25 is extended and provided with a control knob 26 and indicator 28

shown more clearly in Fig. 3. For indicating the direction of pointing of the microphone 17 there is provided an indicator scale 30.

The control motor and operating motor are 5 preferably three phase Selsyn motors, and may be arranged as shown in Fig. 4 or Fig. 5. In Fig. 4, the stators 12F and 25F of the Selsyn motors are connected together by means of conductors 23 to afford the remote control feature, while the 10 rotors 12A and 25A are connected across the three phase supply 29 by means of conductors 21.

In Fig. 5, the stators 12'F and 25'F of the Selsyn motors 12' and 25' respectively, are connected across the three phase supply line 29' by means 15 of the conductors 21', while the two rotors 12'A and 25'A are connected together by means of conductors 23' to afford the remote control feature.

Similar connections may be provided to rotate the boom 11 relative to its standard (not shown). 20 Also a similar arrangement may be provided to move the microphone through a vertical angle if desired.

Baffles and absorbers may be arranged to be actuated with the microphone and amplifier in 25 any of the arrangements described.

In operation, the mixer operator sets all of the microphones in the direction he thinks proper before the commencement of the rehearsal. Then as the scene is being rehearsed he may vary the 30 settings of the control motors and thus the pointing of the microphones until the best results are obtained. He will also note any desired changes to be made during the scene and will upon the actual taking of the "shot" control the microphones to give the optimum results without in 35 any way interfering with the photography or sound recording.

Having thus described my invention, attention is invited to the fact that various modifications 40 may be made therein coming within its scope, and I am therefore not to be limited to the specific embodiment shown and described for the purpose of illustration only but by the actual scope of my invention as set forth in the appended claims.

45 I claim:

1. A microphone mounting comprising a microphone, an amplifier connected to said microphone,

50

phone, a hanger for supporting said microphone, a boom, an operating motor attached to said boom by the field structure thereof, and adapted to support said hanger by the shaft thereof, a control motor the field windings of which are 80 connected to the field windings of the operating motor, and the armature windings of which are connected to the armature windings of said operating motor, a knob mounted upon the shaft of said control motor, a pointer mounted upon said knob, and a stationary scale for indicating the angle of the armature of said control motor, and electrical connections for the windings of said control and operating motors whereby movement 85 of said control motor will be duplicated by a movement of said operating motor.

2. A microphone mounting including an amplifier adapted to support the microphone, a hanger for said microphone, a boom upon which said microphone is adapted to be supported, an operating motor supported by said boom and supporting said hanger, and a control motor connected to said operating motor whereby rotation of said control motor will actuate said operating motor to alter the pointing of said microphone. 95

3. A microphone mounting comprising a standard for said microphone, an operating motor mounted upon said standard, a microphone mounted upon said operating motor, a control 105 motor and connections whereby the operating motor may be controlled by said control motor to vary the pointing of said microphone.

4. A microphone mounting including means for supporting a microphone, adjustable means including an electrical motor supported above said microphone and connected to said supporting means, and means for remotely controlling the operation of said motor to vary the pointing of 110 said microphone. 115

5. A microphone assembly including a beam, a microphone supported in adjustable relation with said beam, a motor coupled to said microphone, and means for remotely controlling said motor to adjust the pointing of said microphone. 120
